RIMLESS METAL SPECTACLE FRONT

Francis B. Neary, Rochester, N. Y.

Application April 12, 1952, Serial No. 19,300

Term of patent 14 years

(Cl. D57—1)

To all whom it may concern:

Be it known that I, Francis B. Neary, a citizen of the United States of America and resident of Rochester, in the county of Monroe and State of New York, have invented a new, original, and ornamental Design for a Rimless Metal Spectacle Front, of which the following is a specification, reference being had to the accompanying drawings, forming a part thereof.

In the drawings:

Figure 1 is a front elevation of a rimless metal spectacle front, showing my new design;

Figure 2 is a top plan view thereof, parts of the temples being shown in broken lines; and

Figure 3 is an end elevation thereof.

The essential features of my design reside in the parts shown in full lines.

I claim:

The ornamental design for a rimless metal spectacle front, substantially as shown and described.

FRANCIS B. NEARY.
